SHUTTLE GUARD

Irvin B. Green, Danville, Va.

Application January 8, 1951, Serial No. 204,846

6 Claims. (Cl. 139—193)

1

This invention comprises novel and useful improvements in a shuttle guard and more specifically pertains to an attachment of an improved construction adapted to be mounted upon the lay swords of looms adjacent the shuttle boxes for deflecting shuttles downwardly into the shuttle boxes, thereby preventing the disadvantages in weaving which are attendant upon inaccurately picked shuttles.

The primary objects of this invention are to provide a pair of shuttle guards of an improved construction and action for guiding the shuttles into the shuttle boxes; to provide shuttle guards having an improved manner of applying the same to a loom; and to provide a shuttle guard construction which may be readily adjusted to compensate for wear in the same during operation.

A still further object of the invention is to provide a shuttle guard having a thread guide member for preventing catching of the shuttle thread upon the shuttle guard during picking of the shuttle.

These, together with various ancillary features and objects of the invention, which will later become apparent as the following description proceeds, are attained by the present invention, a preferred embodiment of which has been illustrated, by way of example only, in the accompanying drawings, wherein:

Figure 1 is a fragmentary elevational view of a portion of a loom of the single end type showing the manner in which the present invention is associated therewith;

Figure 2 is a fragmentary perspective view of a portion of a loom lay and lay sword showing the manner in which one of the shuttle guards is mounted thereon;

Figures 3 and 4 are perspective views respectively of shuttle guards for the left and right lay swords of the loom construction as viewed in Figure 1.

Reference is now made more specifically to the accompanying drawings, wherein like numerals designate similar parts throughout the various views, it being seen that the device is shown as applied to a portion of a conventional loom the same having a pair of lay swords 10 together with a conventional shuttle box arrangement consisting of a plurality of shuttle boxes 12 disposed at the left end of the loom construction, and a single shuttle box 14 at the right end thereof, together with a shuttle 16 adapted to be picked in any conventional manner from the single shuttle box 14 to one of the boxes 12 in accordance with conventional design.

2

It is well known in this art that frequently shuttles when picked between the boxes 12 and 14 tend to rise too high in their path of travel, so that the same do not properly enter the opening of the shuttle box towards which they are directed. This erratic travel of the shuttles and failure to enter the proper shuttle box, gives rise to numerous and time consuming delays in the operation of a loom. Accordingly, previous attempts have been made to provide shuttle guards for the purpose of directing an erratically traveling shuttle downwardly towards the loom box. Heretofore such guards have not been entirely successful for the reason that they were not easily adjustable to compensate for wear upon their guard surfaces; they were not easily installed upon a loom; and frequently their installation resulted in a partial obstruction to the free travel of the shuttles, and interference with the shuttle thread and the like.

The shuttle guard of the present invention is designed to overcome all of these objections in a simplified, economical and convenient manner.

In a single end loom such as that illustrated in Figure 1, the present invention contemplates the mounting of the shuttle guards upon the lay swords 10 above and adjacent the shuttle boxes 12 and 14.

The shuttle guards for the right and left hand lay swords are identical except for two differences which will be pointed out hereinafter.

Each of the guards includes an elongated arcuate metallic plate, that for the left lay sword being indicated at 18, and that for the right lay sword at 20. These plates are of identical dimensions and proportions, except that they are reversed with respect to each other. Thus, what may be termed the inner end of the plate, having the numeral 22 applied thereto for both plates, has a smoothly curving surface directed inwardly and upwardly with respect to the two lay swords as shown in Figures 1 and 2. The outer or rear end of the shuttle guards has a relatively shorter more abruptly upwardly and outwardly curving portion as at 24.

It will be understood that the curvature of the shuttle guards will be so chosen as to enable the same to function most efficiently in deflecting an upwardly flying shuttle downwardly toward the adjacent shuttle box.

Riveted or otherwise securely attached to the convex surface of the plates 18 and 20 is a cushioning lining or sheet of material 26, which may be of any desired character. This cushioning layer is intended to soften or cushion the impact of the shuttle against the guard, and to yield

sufficiently to permit the shuttle to slide or be directed downwardly along the convex undersurface of the guard and towards the adjacent shuttle box.

In accordance with this invention, the shuttle guards are detachably mounted upon the lay swords of the loom and carried thereby. For this purpose, a mounting bracket of the identical construction, and indicated by the numeral 28, is fixedly attached as by welding or the like as at 30 to the upper surface or concave surface of each of the shuttle guards and extends upwardly and laterally therefrom. The bracket 28 extends laterally beyond the side of the shuttle guards 18 and 20, and is provided with an elongated terminal portion 32 which is provided with a vertically elongated slot 34. The plate-like bracket 28 is adapted to rest flush against the inner surface 36 of each of the lay swords 10, and is removably secured thereto as by a fastening bolt 38 which extends through an existing aperture in the lay sword and mounts the shuttle thereon.

The brackets 28 are welded to the plates 22 slightly rearwardly of the central portions of the same.

An abutment in the form of a plate 40 is likewise welded to each of the plates 22 as at 42 and is spaced longitudinally of the plate from the bracket 28 and between the latter and the rearward end of each of the shuttle guard plates. The member 40 may be of any desired character and shape, and could be formed as a part of the bracket 28 if desired. However, as illustrated, the construction has the advantage that the two plate members 28 and 40 may be easily fabricated from steel stampings or the like at a minimum cost, and result in a very simplified construction.

The function of the abutment 40 is to provide a vertical abutment surface which is flush with and rises from the inward edge 44 of each of the plates 22. This abutment surface, as will be apparent from Figures 1 and 2, is adapted to abut against and seat against the front face of the lay swords 10 to thus firmly and securely position the shuttle guards upon the front surface of the lay swords.

As will be readily apparent from Figures 3 and 4, each of the brackets 28 has the forward end of its enlarged portion 32 recessed, cut away or notched as at 46 to provide a clearance between the enlarged portion 32 and the undersurface of the guard. This will insure that the bracket will not be struck by the shuttle 16 as the latter passes the shuttle guard prior to its entry into one of the shuttle boxes 12 and 14.

When the shuttle guard is used with the single end construction of loom shown in Figure 1, it is desirable to provide the guard adjacent the plurality of boxes 12 with a thread guide to prevent entanglement or catching of the thread carried by the shuttle upon the end or corner of the shuttle guard.

For this purpose, a guide member is mounted upon the rear portion 24 of the shuttle guard 18. This guide member, as illustrated, may conveniently comprise an upwardly and transversely disposed guide element 48 having at its lower end a portion 50 by means of which the same is welded or otherwise fixedly secured to the concave upper surface of the shuttle guard 18. Conveniently, this guard member may consist of a wire or strip of spring material, appropriately positioned to

deflect the trailing thread of a shuttle from catching upon the rear end 24 of the shuttle guard 18.

By virtue of the vertically elongated slot 34, it will be apparent that the shuttle guard can be vertically adjusted upon the lay swords 10 in order to compensate for wearing of the cushioning layer 26 and so as to properly position the guard surface for effectively cooperating with the shuttle and the shuttle box despite the variations in operation occasioned by wear of the guard or shuttle.

From the foregoing, the construction and operation of the device will be readily apparent and further explanation is believed to be unnecessary. However, since numerous modifications and changes will readily occur to those skilled in the art after a consideration of the foregoing specification and accompanying drawings, it is not desired to limit the invention to the exact construction shown and described, but all suitable modifications and equivalents may be resorted to, falling within the scope of the appended claims.

Having described the invention, what is claimed as new is:

1. A loom shuttle guard comprising a curved plate, a layer of cushioning material secured to the convex surface of said plate, a bracket secured to the concave surface of the plate and extending laterally therefrom, said bracket having a flat surface adapted to flatly lie against the inside surface of a lay sword, an abutment mounted on said plate and having an abutment surface adapted to abut the front face of a lay sword for positioning said bracket thereon, the loom having a shuttle box, said bracket and abutment positioning said guard adjacent said shuttle box for deflecting a shuttle into said box.

2. The combination of claim 1, wherein said bracket has a cut out portion adjacent the edge of said plate to insure clearance for passage of a shuttle.

3. The combination of claim 1, wherein said bracket and abutment are spaced longitudinally of said plate.

4. The combination of claim 1, including a guide member on said plate for preventing obstruction of the shuttle thread by a corner of the plate.

5. The combination of claim 1, including a guide member on said plate for preventing obstruction of the shuttle thread by a corner of the plate, said guide member consisting of an upwardly and laterally directed finger.

6. The combination of claim 1, including a slot in said bracket for effecting adjustment of said guard upon a lay sword relative to a shuttle box.
